UNITED STATES PATENT OFFICE.

FREDERICK KOHNLE, OF DAYTON, OHIO.

TYPE-HOLDER AND TYPE.

1,197,036.

Specification of Letters Patent. Patented Sept. 5, 1916.

Application filed December 6, 1913. Serial No. 304,960.

To all whom it may concern:

Be it known that I, FREDERICK KOHNLE, a citizen of the United States, residing at Dayton, in the county of Montgomery and State of Ohio, have invented certain new and useful Improvements in Type-Holders and Type, of which the following is a specification.

My invention relates to an improved type holder or chase, and in the type therefor, in which the holder and type as a unit are readily detachable, or removable from the printing device or machine, and each individual type-bar independently positioned and readily removable for quickly changing the set-up.

The holder and type have self-contained characteristics to hold the type against displacement within the holder laterally and longitudinally thereby eliminating the use of any auxiliary spacing or other instrumentalities.

The object of my invention is to provide a typeholder and type primarily for marking machines wherein the marking data is capable of being quickly and conveniently changed and each type-bar definitely located relative to printing spacing with its functions accomplished by a mere inserting or withdrawing of the type from the holder.

Another object of my invention is to provide a slight frictional bind between the type and holder, but in which the friction angle is such as will not interfere with the free and convenient removal of the type, or with its loose function within the printing machine, so as to prevent the type from being dislodged or falling out of the holder pocket when the holder is upturned for examination of the type within the holder.

Another object of my invention is to provide definite linear spacings of the type within the holder, so that it will be in registry with the printing spacing in the printing device or machine, and the material to be printed upon, and in the combination between the type, holder and printing device from which the holder is suspended or supported, with the type loose in the holder, adapted to be engaged by the printing device and relieve the holder of any impact or strains in printing, the printing pressure being directly applied upon the type.

The invention is possessed of all the advantages of the type-chase and type dis-

closed in my prior Patent No. 762,323, dated June 14, 1904, in addition to the advantages and construction herein fully disclosed.

To enable others skilled in the art so fully to comprehend the underlying features of this invention that they may embody the same by numerous modifications of structure, drawings depicting a preferred form have been annexed, as a part of this disclosure, and in such drawings like characters of reference denote corresponding parts throughout all the views, of which:

Figure 1 is a top plan view of the preferred form of holder or chase to which the invention is directed. Fig. 2 is a central vertical section through the chase and portion of the printing or stamping device supporting the chase, with a type-bar illustrated in position for use. Fig. 3 is a perspective view of a type-bar fitting the chase shown in Figs. 1 and 2. Fig. 4 is a top plan view of the chase of modified form of type receiving pockets or openings from that shown in Figs. 1 and 2. Fig. 5 is a perspective view of the type therefor. Fig. 6 is a top plan view of a chase with a second modified form of type receiving pockets or openings. Fig. 7 is a perspective view of the type therefor. Fig. 8 is a top plan view of another modified form of type receiving pockets or openings for the holder provided with tongs to engage with grooved type illustrating a principle of construction from the above described form. Fig. 9 is a perspective view of the type therefor. Fig. 10 is a top plan view of still another modified form in which the type interlocking sockets are of a saw tooth character. Fig. 11 is a perspective view of the type fitting the chase or holder Fig. 10.

As my improved type chase is capable of being mounted or supported within various types of marking machines or printing machines operated by power or hand, I have herein only illustrated a portion of the printing machine or member which moves the type toward and from the work to be printed upon, and therefore herein I will designate the same as a type holder support. This may be within stamping devices known as hand stamps, pin-ticketing machines, price markers or the various types of printing machines wherein a quick and repeated change of the printing set-up is desired or required. The form of connection or method of mounting the type

holder upon the supporting member may be accomplished in numerous ways from that herein illustrated in which the holder is readily removable or detachable.

- 5 The construction of the holder support and the holder is immaterial as far as the features of this invention are concerned, but merely in provision for detachability of the holder from the support and possessed 10 of a characteristic in that the type is supported in its normal position below a platen or plane surface which may engage with the top of the type to bring the printing pressure directly upon the type; the type being 15 sufficiently loose within the holder to relieve the holder of any printing impact or strains.

I will first describe the type holder and type as the primary feature of my invention, with reference to Figs. 1, 2, and 3 20 which disclose the preferred form.

The type holder 1 is provided with one or a plural number of openings 2 of rectangular form vertically extended through the 25 holder to receive the type and allow the same to extend therethrough and project beyond the top and bottom surfaces thereof. The pockets or openings are provided with the grooves 3 tapering vertically and 30 equally spaced from each other, and the point of the groove preferably terminates a slight distance above the bottom surface of the holder, but the groove may extend completely through the holder. These grooves 35 provide sockets for the type-bar for independently supporting each type-bar against lateral displacement and definitely locates each type-bar within the holder and retains the same therein without the employment 40 of auxiliary clamping means for no locking up of the type is required. The grooves 3 are adapted to receive the rib or tongue 4 of the type-bar 5. The ribs are tapered correspondingly with the grooves and in a 45 single character type-bar preferably project from the medial portion of the bar, which is rectangular in cross-section and of such size so that the type in a line may abut each other as in setting up of ordinary type. They 50 may also, if the data requires, be spaced apart in divisions of the width of a single type-bar and maintained in vertical alignment by the tongue and groove engagement. It is obvious, however, that the type may be 55 of greater width than that of a single character bar, containing a line or word in which instance a single rib will suffice. Each type, therefore, has its independent mounting and is not dependent upon its adjacent type to hold it in its position, and its 60 location is definite relative to the printing spacing on the tag or work printed upon.

The angle or taper of the groove and tongue renders it possible to slightly bind 65 the type in their position within the chase,

a slight finger pressure being sufficient, which will not interfere with their removal, but which will hold the type when the chase is upturned. This permits the operator to examine the face of the type to see whether 70 the data is set correctly. The tongues also limit the downward movement of the type within the holder and also serve as an indicator, and absolutely prevent the character from being placed in an inverted position. 75 Each type-bar is provided with a notch 7, forming a lip 8, affording means for the operator to engage with his finger-nail for withdrawing the type.

The chase is constructed to be detachably 80 mounted within the machine supporting member and the construction illustrated is comprised as follows:—The type chase or holder 1, has a lateral flange extension 10 projecting from the upper edge of the opposing sides of the chase. The flanges slidably fit into the groove of the depending limbs of the support 9 and beneath the plate 11, with a clearance provided between the plate and upper surface of the chase to receive the projecting type. The type under normal conditions do not engage with the plate, affording a slight clearance between the type and plate for easy insertion or removal of the chase from the support. This 90 offers a further advantage in that the type are moved upwardly to engage the plate when they are brought against the printing platen or work support, which absolutely relieves the chase of printing strains, bringing 95 the printing pressure directly upon the type. As the type chase is preferably made from what is known as the die casting to reduce its cost of manufacture, and avoid complicated machining in making the openings or pockets and grooves with very thin separating walls, the chase is not capable of 100 withstanding any severe strains. The holder support has a definite reciprocating or printing motion, and therefore, to regulate the density of the impression I provide insert-filling pieces 13 or cushion between the type and plate 11. In the construction shown this is accomplished by providing a second pair of opposing grooves in the limbs of the type chase support adapted to receive and loosely support the insert-filling pieces 13. These can be substituted by others of different thickness, and they also serve as weights to force the type downwardly during the normalizing movement of the support so that the type will always be free from the plate 11, in withdrawing the chase. This prevents marring the upper 110 surface of the type.

In the modified form of construction shown in Figs. 4 and 5 the tongue 4 is of V-form in cross-section and at its upper end may extend to the width of the type. In Figs. 6 and 7 the tongue and 115

groove are of curved form. Figs. 8 and 9 show an alternative arrangement from the preceding described figures, in that the tongue element projects from the walls of 5 the opening instead of the type. Figs. 10 and 11 show a saw-tooth form of interlock between the type and chase. In all the forms, however, a general characteristic is common to all, in that a tapering or graduated 10 interlock is provided between the type and its chase to hold each individual type in independent or perpendicular position within the chase and against lateral displacement without the aid of auxiliary clamping 15 means.

Having described my invention, I claim:—

1. The combination with a type supporting member having a type receiving opening therethrough provided in one wall thereof 20 with an angular notch, of a type-bar adapted to engage through the opening and having an angular tongue projecting to engage said notch and support the type-bar in said member.

25 2. The combination with a type supporting member having a socket provided at one side thereof with an inclined surface, of a type-bar adapted to enter said socket and having a portion provided with an inclined 30 surface to engage the inclined surface of said socket and support said type bar in said socket.

35 3. A type-bar having an inclined rib projected from one side, adapted to engage into a holder socket for supporting the bar within the socket.

40 4. A type-bar having a wedge element projecting from one side thereof adapted for supporting the bar longitudinally and laterally within a holder socket.

45 5. A type-holder having a rectangular opening, one wall of said opening being provided with a series of parallel sockets, extending to the top of said walls, and a type bar adapted to engage through said opening and having a wedge element projecting from one side to engage into one of said wall sockets for supporting and laterally confining said bar within the 50 holder.

55 6. The combination, with a type supporting member having a socket provided at the upper end of one side thereof with an upwardly and outwardly inclined surface, of a type bar adapted to enter said socket and having near its upper end a laterally ex-

tending portion provided with an upwardly and outwardly inclined surface to engage the inclined surface of said socket and support said type bar in said socket. 60

7. The combination, with a type-supporting member having a socket provided at one end thereof with a guideway having an upwardly and outwardly inclined surface extending to the top of said socket and providing the same with an enlarged upper end, of a type bar adapted to enter said socket and having a laterally extending portion to enter the enlarged end of said socket and provided with an upwardly and outwardly inclined surface to engage the inclined surface of said guideway and support said type bar in said socket. 65 70

8. The combination, with a type-supporting member having a socket provided at one side thereof with a guideway having an enlarged upper portion, of a type bar adapted to enter said socket and having a portion forming a guide to coöperate with said guideway, said portion having an enlarged 80 upper end to enter the enlarged portion of said guideway and support said type bar.

9. The combination, with a type-supporting member having a socket provided at one side thereof with outwardly converging 85 walls forming a guideway and having their upper ends flared, of a type bar adapted to enter said socket and having at one side thereof outwardly converging walls forming a guide to coöperate with said guideway 90 and having their upper portions flared to be engaged and supported by the flared portions of said guideway.

10. A type-holder having a rectangular opening therethrough, one wall of said opening provided with a plurality of definitely spaced inclined surfaced sockets extending to the top of said wall, and a series of type bars adapted to engage through said holder opening, each bar having an inclined element projecting from one of its sides to engage into a socket for supporting and laterally confining the bar, whereby said type-bars of a series may be supported in relative abutting or spaced positions within said 105 holder opening.

In testimony whereof, I have hereunto set my hand.

FREDERICK KOHNLE.
